UNITED STATES PATENT OFFICE.

JAMES W. P. TAYLOR, OF WASHINGTON, DISTRICT OF COLUMBIA.

SHEET-JOGGING DEVICE FOR PRINTING-PRESSES.

SPECIFICATION forming part of Letters Patent No. 738,641, dated September 8, 1903.

Application filed April 30, 1903. Serial No. 154,992. (No model.)

To all whom it may concern:

Be it known that I, JAMES W. P. TAYLOR, a citizen of the United States, residing at Washington, in the District of Columbia, have invented certain new and useful Improvements in Sheet-Jogging Devices for Printing-PresSES, of which the following is a specification.

My invention relates to devices employed in connection with the delivering mechanism of printing-presSES for automatically "jogging" or evenly delivering the sheets of paper as they are successively delivered by the flier on the fly board or table.

The invention consists in the improved means for evenly delivering the paper hereinafter described, and illustrated in the accompanying drawings, in which—

Figure 1 is a perspective view of the flier and fly-board of a printing-press and my improved jogging device or devices for evening the sheets of paper combined therewith. Fig. 2 is an enlarged side elevation of one of the jogging devices. Fig. 3 is a rear view of the same. Fig. 4 is a central vertical section of the device shown in Figs. 2 and 3. Fig. 5 is a rear view of part of one of the jogging devices provided with a contact-piece different in construction from that illustrated therewith in the other views. Fig. 6 is a perspective view of one of the adjustable stops or gages.

In the accompanying drawings, A designates the flier of a printing-press, and B the fly-board upon which the sheets are delivered from the flier. These parts may be of any usual or approved construction and used in connection with any preferred style of printing-press. The flier is mounted upon the shaft C and has a number of sticks a, that are connected with the shaft C in any suitable way. The fly-board is provided upon its upper surface with a number of slightly-raised dovetail ribs 2, upon which are mounted the adjustable gages or stops 3, with which the edges of the sheets of paper are made to engage as the latter are delivered upon the fly-board and which operate to hold the sheets evenly laid one upon the other. The gages or stops 3 have relatively broad feet or bearings at their lower ends in which are formed dovetail grooves 4, that fit the

ribs 2. To hold the stops in place, each of them is provided with a lever or clamping arm 5, that has a fulcrum or pivot about which it moves and which also serves as a connection between the lever and the body of the stop or gage. A convenient manner of mounting the lever or clamping arm 5 is that illustrated, wherein it is shown as being arranged between lugs or flanges 7, carried by the gage and to which it is pivoted, as indicated at 6. A set-screw 8 is employed to adjust the clamping-arm 5 and to force it into engagement with one edge of the rib 2, as clearly indicated in Fig. 3 of the drawings, whereby the stop or gage is securely held in any position to which it may be adjusted. By thus constructing the gage I am enabled to mount it entirely above the receiving-table or fly-board, which therefore does not have to be slotted or perforated for the gage or its attaching means and to firmly support it upon a rib of so slight elevation above the surface of the board that it will not interfere to any practical extent with the smooth and uniform laying of the sheets. The stops may be easily and quickly adjusted while the press is in motion, and being entirely above the upper surface of the delivery-board they are always in sight and easily accessible.

The paper-jogging devices are arranged to be operated directly by the flier and are also situated entirely above the delivery-board, being constructed so as to be mounted upon the ribs 2. The main frame 9 of each jogging device is provided at one side with a clamp consisting of a lever 5 and set-screw 8, similar to that already described in connection with and for holding the stop 3. In the frame or body 9 of the jogging device there is mounted a horizontally-movable bar 11, carrying at its rear end the jogging or pushing plate 10, that engages with the edges of the sheets as they are delivered from the flier and pushes them into place between the stops or gages 3. A bell-crank lever 12 is mounted upon a suitable shaft 13 in the frame of the jogging device and has one of its arms connected with the horizontally-movable bar 11, while its other arm is connected with a vertical movable slide 14, that is mounted in suitable ways in the upper por-

tion of the frame 9. A coiled spring 15 (or preferably a pair of such springs reversely coiled) bears against the lever 12 and operates to normally hold the jogger-plate 10 outward and the slide 14 raised. The upper end of the slide 14 is provided with a contact-piece 16, arranged in the path of one of the fly-sticks *a*, so that when the latter moves downward to deliver a sheet it engages with such contact-piece and moves the slide 14 downward and the pusher or jogger plate inward at the instant the sheet is delivered upon the receiving or fly board. The moment the flier begins its return movement the spring or springs 15 restore the parts to their normal position—that is, with the plate 10 moved outward and with the slide and contact-piece elevated—this movement operating to push the last-delivered sheet between the stops 8, 20 directly above the previously-delivered sheet, where it is held by the jogger or pusher plate 10, this being normally held in engagement with the edges of the sheets by the springs 15.

The distance between the upper surface of the fly-board and the under surface of the flier-sticks differs in different machines and sometimes in the same machine, according to the nature of the flier and delivery-board being employed, and it is therefore desirable to be able to make provision for having the jogging devices accurately operated no matter what the relation of the flier and fly-board may be. Accordingly I prefer to mount the contact-piece 16 upon a screw 17, which secures it to the slide 14 and to arrange between such slide and the contact-piece a spacing sleeve or piece 18. If the flier fingers or sticks are relatively high above the delivery-board, a long screw and spacing sleeve will be employed, whereas if they are closer together shorter parts will be used. It sometimes happens that it is desirable to arrange the delivery-board very close to the flier when in its lowermost position. In such case the jogging devices shown and described may be too high to have the flier-sticks engage directly with the contact-piece 16. Under these circumstances the fly-sticks are adjusted so as to straddle the jogging devices, and a yoke-shaped contact-piece 19 (see Fig. 5) is secured to the contact-piece 16 or used in place thereof. This yoke-shaped contact-piece has laterally-extended depending arms arranged to be engaged by the two flier-sticks *a* on either side of the jogger. Two or more jogging devices will usually be employed, according to the size of the sheet being delivered.

Among the advantages incident to my invention the following may be mentioned. It is entirely practicable to adjust the jogging device as well as the gages while the press is in operation. This is due in part to the fact that the gages and jogging devices are entirely above the delivery-board, which renders them both easily accessible and fully exposed to view. The operating mechanism of

the jogging device is exceedingly simple, and by properly proportioning the length of the arms of the bell-crank lever to each other the requisite amount of movement can be imparted to the jogger or sheet-engaging plate or member whether the slide 14 have a relatively long or short movement. Further, it will be observed that the sheet-engaging plate 10 remains in contact with the sheets that have been delivered throughout most of the time, being retracted only just before the sheet is delivered by the flier.

Having described my invention, what I claim, and desire to secure by Letters Patent, is—

1. The combination with the delivery-board of a printing-press provided with guide-ribs, of the adjustable means for evening the sheets delivered to such table, arranged to slide upon the said ribs, and each provided with a pivoted clamping-arm arranged to engage with the said rib and hold such means in place, substantially as set forth.

2. The combination with a delivery-board of a printing-press provided with dovetail ribs 2, of the means for evening the sheets delivered to the board arranged to slide upon the said ribs, and each provided with a clamping-arm 5 arranged to engage with the edge of the rib, and a set-screw for operating the clamping-arm, substantially as set forth.

3. The combination with a delivery-board and flier of a printing-press, of a jogging device arranged to be operated by the flier and comprising a member for engaging with the edge of the paper, arranged entirely above the delivery-board and movable in a path parallel therewith, a contact-piece with which the flier engages movable in a path at right angles to the said paper-engaging member and also arranged entirely above the delivery-board, and connecting means between the said parts also arranged entirely above the delivery-board, substantially as set forth.

4. The combination with the delivery-board of a printing-press, of a jogging device comprising a supporting-frame arranged above the delivery-board, a reciprocating paper-engaging member mounted in the said frame and movable in a path parallel with the face of the delivery-board, a contact-piece also mounted in the frame and movable in a path at right angles to that of the paper-engaging member, and operating connecting mechanism between the said movable members also mounted in the said frame, substantially as set forth.

5. The combination with the receiving-board and the flier of a printing-press, of a horizontally-reciprocating member for engaging the edge of the sheet of paper and pushing it into place, a spring for automatically moving said member against the paper and maintaining it in contact therewith, and a contact member connected with the said horizontally-movable, paper-engaging member arranged to be operated by the flier when

the latter descends to deliver a sheet and retract the paper-engaging member against the action of its spring, substantially as set forth.

6. The combination with the delivery-board 5 and the flier of a printing-press, of a jogging device comprising a frame adjustable relative to the delivery-board and situated above the same, a paper-engaging member movable in the said frame, a contact member arranged 10 to be engaged by the flier also mounted in the said frame, and connections between the said contact and paper-engaging members, substantially as set forth.

7. In a sheet-jogging device for printing-presses, the combination of a reciprocating paper-engaging member, a contact member arranged to be engaged by the flier as it comes down to deliver the sheet, and a bell-crank lever connecting the said members, 20 substantially as set forth.

8. In a sheet-jogging device for printing-presses, the combination of a reciprocating sheet-engaging member, a spring arranged to hold the same against the sheet after it has 25 been delivered, an operating member arranged to move at right angles to the sheet-engaging member and to be engaged by the flier as it comes down to deliver a sheet, and a bell-crank lever connecting the said sheet-

engaging and operating members, substantially as set forth. 30

9. The combination of a delivery-board provided with a rib 2, of a sheet-jogging device comprising a frame 9 adjustable upon the said rib, a clamp for holding the same in 35 position, reciprocating means for pushing or jogging the sheet, a bell-crank lever mounted in the frame and connected with the said jogging means, a spring engaging with the bell-crank lever and arranged to hold the 40 jogging means in position to even the sheets, and a contact-piece 16 connected to the bell-crank lever and arranged to be operated by the flier of a press, substantially as set forth.

10. The combination with the delivery- 45 board and the flier of a printing-press, of a jogger supported by the delivery-board, and means for securing the jogger in place upon said board, the jogger being arranged to be engaged directly by the flier as it approaches 50 the end of its delivery movement, whereby it is automatically operated to engage with and shift the sheet being delivered, substantially as set forth.
